UNITED STATES PATENT OFFICE.

ROY E. JORDAN, OF NEWARK, NEW JERSEY, ASSIGNOR TO THE MOSAIC TILE COMPANY, A CORPORATION OF OHIO.

DESIGN FOR A BAR AND SHELF BRACKET.

Application filed March 4, 1924. Serial No. 8,827. Term of patent 14 years.

To all whom it may concern:

Be it known that I, ROY E. JORDAN, a citizen of the United States, residing at Newark, county of Essex and State of New Jersey, have invented a new, original, and ornamental Design for a Bar and Shelf Bracket, of which the following is a specification, reference being had to the accompanying drawing, forming part thereof.

The figure is a perspective view of a bar and shelf bracket, showing my new design. I claim:— The ornamental design for a bar and shelf bracket, as shown.

ROY E. JORDAN.
